UNITED STATES PATENT OFFICE

142,769

DESIGN FOR AN AUTOMATIC EMERGENCY LIGHTING UNIT OR SIMILAR ARTICLE

Harold S. Bird, Belmont, Mass.

Application May 11, 1945, Serial No. 119,490

Term of patent 14 years

(Cl. D48—24)

To all whom it may concern:

Be it known that I, Harold S. Bird, a citizen of the United States and a resident of Belmont, county of Middlesex, and State of Massachusetts, have invented a new, original, and ornamental Design for an Automatic Emergency Lighting Unit or Similar Article, of which the following is a specification, reference being made to the accompanying drawing, forming part thereof.

In the drawing:

Fig. 1 is a plan view of my automatic emergency lighting unit, showing my new design;

Fig. 2 is a side view of same, and

Fig. 3 is an end view.

I claim:

The ornamental design for an automatic emergency lighting unit or similar article, substantially as shown.

HAROLD S. BIRD.
